COMBINATION WINDOW AWNING AND CAGE STRUCTURE

John P. Francis, 20 Boston St.,
Haverhill, Mass. 01830

Filed Sept. 4, 1968, Ser. No. 13,387

Term of patent 14 years

Int. Cl. D25—02

U.S. Cl. D13—1

FIG. 1

FIG. 2

FIG. 3

FIGURE 1 is a perspective view of a combination window awning and cage structure, embodying my new design,

FIG. 2 is a side elevation view, with the awning in a vertically spaced apart position above the cage structure, and

FIG. 3 is a side elevation view, wherein the awning has been moved downwardly, and repositioned on the cage structure.

The window structure fragmentarily shown in broken lines in FIGS. 1, 2 and 3 is included for illustrative purposes only.

I claim:

The ornamental design for a combination window awning and cage structure, substantially as shown and described.
